UNITED STATES PATENT OFFICE.

DEMETRIOS P. PAPAPAVLOU, OF WASHINGTON, DISTRICT OF COLUMBIA.

ALARM APPARATUS.

1,283,282.

Specification of Letters Patent. Patented Oct. 29, 1918.

Application filed November 10, 1916. Serial No. 130,615.

To all whom it may concern:

Be it known that I, DEMETRIOS P. PAPAPAVLOU, a subject of the King of Greece, residing at Washington, in the District of Columbia, have invented certain new and useful Improvements in Alarm Apparatus, of which the following is a specification.

This invention has relation to improvements in alarm apparatus and it comprises, more particularly, an improved device that is designed to be used in connection with doors, windows and other structures of a like nature, to detect, in the first case, the turning of the door knob in either direction and thus cause the ringing of an alarm, and in the second case or when used in connection with a window, to cause the ringing of an alarm upon the slightest opening movement of the window sash.

20 A further object of the invention is to provide a device of the type in question that is extremely simple in construction, strong and durable, and highly practical from both the standpoint of the manufacturer and the 25 standpoint of the user; and which, it is believed, may be manufactured at a comparatively low cost.

Various other objects and advantages will become apparent during the continuance of 30 the following description.

These objects are accomplished by such means as are shown in their preferred form in the accompanying drawings, described in the following specification and then more 35 specifically pointed out in the appended claims.

In the accompanying drawings wherein like characters designate like parts throughout the several views:

40 Figure 1 is a view in front elevation showing my invention as in its preferred embodiment, applied to a door and door knob of conventional form,

Fig. 2 is a view in section of my invention 45 taken on the line 2—2 of Fig. 3,

Fig. 3 is a view in section taken on line 3—3 of Fig. 2.

Fig. 4 is a view in cross section of the door, showing a part of the door knob 50 broken away to show the manner of attaching certain parts of my invention thereto,

Fig. 5 is a view in plan showing my invention in a slightly modified form and as used in connection with a window sash of 55 conventional form,

Fig. 6 is a view in section taken on line 6—6 of Fig. 5,

Fig. 7 is a view in section taken on line 7—7 of Fig. 5, and

Fig. 8 is a view showing my invention in 60 a slightly modified form such as adapted to be used in connection with a door latch.

Referring now more particularly to that embodiment of my invention shown in Figs. 1 to 4 inclusive, 10 designates a door of any 65 desired form, 11 indicates a sleeve that engages a spindle as shown in Fig. 4, while 12 designates a door knob of conventional form.

In the present embodiment of my invention 70 13 is a suitable casing in which is arranged certain clock-work mechanism, which consists in part of a main spring 14, a gear wheel 15, a pinion 16 with which said gear wheel meshes and a ratchet wheel 17. Such mechanism is preferably carried on shafts 75 18 and 19, although any other arrangement may be provided if desired.

In connection with the clock work mechanism above described, I arrange on the shaft 20, an oscillating member 21 to co-act with 80 the wheel 17, said member being adapted for oscillation by said wheel 17 upon release of the latter, as will be subsequently set forth. The member 21 is also designed to operate a hammer 24 to ring the bell 25. 85

Dog 26 is pivotally mounted as at 27, its forward end portion normally engaging the wheel 17 to prevent operation thereof while its other end lies in the path of movement 90 of certain actuating means as will be subsequently described.

On the upper side of the casing 13 I arrange a hollow standard or other support 28 through which is passed an actuating rod 29. At its inner end rod 29 may be slightly 95 enlarged as at 30 to properly engage one end of the dog 26 while at its outer end it carries an operating portion 31 to facilitate the proper thrusting thereof such as will result in the rocking of the dog 26 and the 100 release of the wheel 17. Intermediate its ends the rod is provided with a slightly enlarged squared portion 32 which passes through a complementary opening in the casing thus preventing turning movement of 105 the rod without forming any impediment to the operation thereof. On the other hand standard 28 is provided with a transverse partition 33 through which the rod extends and against which bears an expansion coil 110

spring 34 whose other end bears against a stop member 35 of the rod. As will be readily seen upon reference to Fig. 2, the purpose of this spring is to normally retain the rod 5 in its outermost position.

When using my invention as shown in Fig. 1, I provide the sleeve 11 of the door knob with a collar 36 which is preferably fixed thereto as at 37, while from said collar depend diverging arms 38 and 39. Rods 40 are loosely connected at their upper ends as at 41, to the lower ends of the said arms. A guide 42 of suitable construction is positioned on the door slightly above the operating portion of the actuating rod 29, the purpose of this guide being to retain rods 40 in engagement with the operating portion as is clearly shown in Fig. 1.

From the above it will be obvious that upon turning of the knob 12 in either direction one of the rods 40 will be thrust downwardly thus causing a like movement of the actuating rod 29 against the tension of the expansion spring 34, rocking the dog 26 to release the wheel 17 so as to permit operation of the clock work mechanism and the consequent ringing of the bell 25.

In the embodiment shown in Figs. 5 to 7 inclusive I secure the casing 13 to the window frame or other support 43, at any desired location and preferably on the inner side of the frame. I further provide the standard 28 with an extension, or rather an addition 44, which may be in the form of a housing such as clearly shown in Fig. 6, which serves to pivotally support as at 45 an actuating lever 46.

The free end of actuating lever 46 normally engages the operating portion 31 of the rod 29, while its other end portion is bent to form an arm 47 that extends to a point adjacent the sash 48 and which connects with a link 49. Link 49 in turn connects with a spring 50, while the spring 50 in turn connects with a rod 51 which has a portion 52 for connection with the sash. The portion 52 of the rod 50 may be embedded in the sash or else it may simply be engaged with the upper face thereof as shown in Fig. 7. In any event the slightest upward movement of the sash will cause a rocking of the lever 46 and the consequent actuation of the alarm apparatus. However the spring 50 will compensate for the varying heights to which the window may be raised thus avoiding the breaking of any of the parts of the apparatus.

In Fig. 8 I have shown the usual latch-operating portion of a door, such as designated by the numeral 53, provided with a depending rod 54 such rod being, of course, capable of moving the actuating rod 29 of my device should I desire to use my invention in connection with a door having that type of securing means.

While not absolutely necessary, I may provide means to lock the operating mechanism against movement so that the door or window, which ever the case may be can be opened or closed without causing the operation of the alarm device. To this end I provide casing 13 with a transverse shaft 22 that extends above the gear wheel 15 of the operating mechanism (see Fig. 2) and which carries in alinement with said gear a lug or detent 22' that is adapted to intermesh with and prevent rotation of said gear wheel. Of course, when the detent is in the position shown in Fig. 2 the mechanism will be allowed to operate just as soon as it is released by the dog 26. Likewise, I may if desired provide means such as shown at 29' whereby the length of the actuating shaft 29 may be regulated by the operator.

From the foregoing it is believed that the advantages and novel features of my invention will be readily understood and therefore further detailed description is deemed unnecessary.

In reducing the invention to practice, it will be found that the form referred to herein as the most practical and preferred embodiment is the most efficient, but realizing that certain conditions will necessarily vary in concurrence with the adoption of the device, it is emphasized that various minor changes in the details of construction and in the proportion of parts may be resorted to when required without sacrificing any of the advantages of the invention, as defined in the appended claims.

Having thus fully described the invention, what is claimed as new and desired to be secured by Letters Patent is:

1. An alarm device including a casing, a hollow standard extending outward from the casing, alarm mechanism within the casing, a rod extending through said hollow standard and being longitudinally movable and non-rotatable and operable to control said alarm mechanism, and a connecting device correlated with said rod and with the exterior object so as to cause operative movement of said rod upon movement of said exterior object.

2. An alarm device comprising a casing having a hollow standard extending outward therefrom, alarm mechanism including a bell within said casing, means for actuating the alarm mechanism, means for detaining the alarm mechanism against actuation, an actuating rod mounted to move longitudinally through said standard and to control the last said means, said actuating rod being broadened at its upper end and adapted for disunited contact with an element in connection with a door or window, so that the alarm will be operated upon movement of the door or window.

3. In an alarm apparatus of the class de-

- scribed, the combination with a window frame of a casing positioned on said window frame, alarm means associated with said casing, means to operate said alarm means, means to normally retain said operating means against movement, an actuating rod adapted to move said last mentioned means to release said operating means, an extension on said casing, a lever pivoted on said extension having one end in engagement with said actuating rod, a link connected with said lever, a resilient member connected with said link, and means carried by said resilient member for connection with the window sash whereby upon movement of said sash said lever will be rocked to move said actuating rod, substantially as described.
4. In a device of the class described, the combination of a casing, an alarm mechanism carried within said casing, a hollow standard formed upon said casing, an actuating rod extending through said standard and projecting into said casing, said rod having a squared portion engaging said casing, whereby the rod will be held against
- 5 rotary movement, means for normally urging said rod in one direction and means for forcing said rod inwardly against the urgency of the last mentioned means, thus causing said rod to cause the operation of said alarm mechanism.
5. In a device of the class described, the combination of a casing, an alarm mechanism carried within said casing, a hollow standard projecting above said casing, a lateral extension formed upon the upper end of said standard, a reciprocally mounted actuating rod carried by said standard and projecting into the casing, a lever pivotally mounted upon said lateral extension and engaging the outer end of said rod, means for shifting said lever, thus causing said lever to move said rod for causing the operation of said alarm mechanism.
- 20 In testimony whereof I affix my signature in presence of two witnesses.
- 25 . DEMETRIOS P. PAPAPAVLOU.
